STRIP COILING APPARATUS

Max H. Bursk, Fribourg, Switzerland, assignor to Lee
Wilson Engineering, S.A., Fribourg, Switzerland
Filed Feb. 17, 1965, Ser. No. 433,421
10 Claims. (Cl. 242—80)

This invention relates to apparatus for processing and handling coils of strip metal.

In the open coil process of treating strip metal in coil form a tight wound coil of metal strip is recoiled into open or loose coil form in which the laps of the coil are spaced apart from each other. This open coiling operation is customarily effected by recoiling a tight wound coil of metal on a vertical axis turntable while winding in between the laps of the coil a spacer strand of the proper size to give the desired lap spacing.

After an open coil of strip is subjected to the desired treatment it is usually necessary to rewind the open coil back into tight coil form for further handling and processing. The apparatus of the present invention greatly expedites and simplifies the handling of untreated tight coils of strip metal prior to and during open coiling thereof and expedites and simplifies the recoiling of a treated open coil back into tight coil form and the subsequent tilting of the tight coil into horizontal axis position for further handling.

The apparatus of the present invention is also adapted to receive horizontal axis coils of strip from a conveyor and rapidly and accurately locate and support them in horizontal axis position for pay off to a temper mill or other strip processing apparatus.

It is an object of the present invention to provide an improved apparatus for processing and handling coils of strip metal which eliminates certain coil lifting operations, by magnets or other lifting devices, required by prior mechanisms, thus substantially reducing the coil handling time and eliminating the coil up-ending devices which are presently required to tilt the coils from horizontal axis to vertical axis position and vice versa.

Other objects include the provision of strip coil handling apparatus which does not require the use of separate coil up-ending devices such as have previously been employed to tilt the coils from horizontal axis position to vertical axis position and vice versa; and the provision of strip coil processing and handling apparatus whereby the output of a tight or open coil strip processing installation may be increased, the operating costs reduced, and the possibility of damage to the edges of the strip in the coils greatly reduced.

For the achievement of the aforementioned objects the coiler apparatus of the present invention, broadly speaking, embodies a frame member mounted for pivotal movement, a pair of rotatable mandrels operably mounted on this frame member, means for rotating the mandrels on the frame, and means for pivoting the frame member in conjunction with the mandrels. More specifically, the frame member is mounted for pivoting about a substantially horizontal axis of rotation and rotatably supports a coil support or turntable at each end, a collapsible and expandable mandrel being associated with each turntable for rotation therewith, said mandrels in some cases being of different sizes to permit paying off of coils of one core size and winding on of coils of another core size to prevent coil breaks in the strip metal after it has been annealed. Furthermore, coil infeed and outfeed conveyor means are provided which cooperate with coil hoist means for applying and removing coils to and from, respectively, the aforesaid mandrels when the frame member is pivoted into corresponding selected positions.

Other features, objects and advantages of the inven-

2

tion will become apparent by reference to the following detailed description and drawings wherein like reference numerals are employed in the various embodiments for the same or analogous elements and in which:

5 FIGURE 1 is a perspective view of apparatus embodying the present invention designed particularly for use in the open coil process and including the coil conveying and lifting equipment associated therewith;

10 FIGURE 2 is a view, partially in cross-section, of the coiler apparatus depicted in FIGURE 1; and

FIGURE 3 is a plan view, partly in horizontal cross-section, of a somewhat modified form of my apparatus also designed particularly for use with open coils.

15 FIGURE 4 is an enlarged fragmentary view illustrating in greater detail the clutch mechanism between the turntables and the drive means of the apparatus of FIGURES 2 or 3.

20 FIGURE 5 is a perspective view of a modified form of my invention which is particularly designed for transferring horizontal axis tight coils from a conveyor into position for feeding the strip to a rolling mill and rotatably supporting the coil during pay-off to the mill.

25 Referring now to the drawings, with particular attention to the embodiment of FIGURES 1 and 2, it will be seen that tightly wound coils 1 are delivered from a suitable supply depot (not shown) into close proximity with the coiler unit (which is generally indicated by the reference character 3) by suitable infeed conveyor means such as the chain conveyor 2.

30 A coil hoist car 4, having wheels 5 adapted to travel upon rails or tracks 6 and actuated by suitable means such as a hydraulic cylinder (not shown), is adapted to be moved beneath the forwardmost infeed tight coil 1 into a position to raise the latter off the conveyor 2. The coil hoist platform 7 of the coil hoist car 4 can be raised by means of a hydraulic cylinder 8 in order to lift the forwardmost coil 1 into a position such that its open center or eye is in alignment with the collapsible and expandable pay off mandrel 9 when such is disposed in horizontal axis position, as will be more fully explained hereinafter.

35 A similar coil outfeed chain conveyor means 29 is located at a diametrically opposed location from the previously described coil infeed conveyor 2. Here again, a coil hoist car 10, incorporating a coil hoist platform 11 adapted to be raised and lowered by a hydraulic cylinder 12, is associated with the conveyor means 29. This coil hoist car 10 includes wheels 13 which travel upon the rails 14 and the car may be moved on the rails by a hydraulic cylinder or other suitable means (not shown).

40 As will be explained more fully later, the outfeed conveyor 29 receives annealed coils 1b from the expandable and collapsible mandrel 15 of the coiler unit 3 and extends in the opposite direction from the infeed conveyor 2.

45 It is advantageous to provide a larger diameter mandrel for winding annealed strip metal back into a tight coil in order to prevent coil breaks that may occur if the original size mandrel is employed. For this reason the tight-rewinding mandrel 15 is preferably larger in diameter than the pay off mandrel 9. By way of example but not limitation, in apparatus for coiling strip steel the pay off mandrel 9 may have a diameter of 24 inches while the tight winding mandrel may have a diameter of 36 inches.

50 Without considering at this point the details of the construction of the coiler unit 3, it should be appreciated that the expandable mandrels 9 and 15 can be rotated, for example in opposite directions, by a drive motor 16. This motor has a brake 17 effective on the outer end of its shaft and is connected to the mandrels 9 and 15 through a coupling 18, a gear reducer 19, a further cou-

pling 20, shaft 23 and suitable gear and clutch mechanisms located within the housing 21 of the coiler 3 and which will be described in detail shortly. It should further be appreciated that the coiler unit 3 is so constructed that the expandable and collapsible mandrels 9 and 15 can be simultaneously swung or rotated about the extended center line of shaft 23 in a substantially vertical plane from the vertically extending positions shown in the drawings into horizontally extending positions and returned to vertical position.

The operation of the apparatus of FIGURES 1, 2 and 3 will now be explained. Let it be assumed that the coiler unit 3 has been rotated from the vertical axis position of FIGURE 1 into its horizontal position with the axes of the mandrels 9 and 15 extending horizontally and with the smaller diameter mandrel 9 collapsed and in position to receive an unannealed cold rolled coil of strip steel 1 from the coil hoist car 4. To effect transfer of the coil to mandrel 9 the hoist car 4 is moved on the tracks 6 so that the center opening in coil 1 is moved over the mandrel 9 until the end of the coil is adjacent the turntable 37 of the coiler 3. The hoist platform 7 is then lowered and at the same time the mandrel 9 is expanded, thereby securing the coil in place on the mandrel. Thereafter, the coiler 3 is rotated 90° in the direction of the arrow in FIGURE 1 into vertical position with the mandrel 9 extending upwardly as seen in FIGURE 1. The tight coil 1 may then be payed off onto a suitable loose coil turntable (not shown) to produce a loose or open coil ready for further treatment. The loose coil turntable and ancillary equipment have not been shown since details thereof are not necessary to understanding, and form no part of, the present invention.

After paying off of the tight wound coil 1 from mandrel 9 has been completed the coiler 3 is rotated 180° (the hoist cars 4 and 10 having been backed out of the way) to bring the larger diameter mandrel 15 into upstanding vertical operating position to accept for tight rewinding the strip from a treated loose or open coil which has been placed on an adjacent loose coil turntable (which as noted above is not shown in the drawings). It will be understood that it is possible to use the coiler unit 3 with only a single loose coil turntable, but it is preferable to provide two loose coil turntables in order to permit better continuity in operation.

The outer end of the strip of the open coil which is on the loose coil turntable is fed into suitable gripper means (not shown but which may be of any well known type) on the larger diameter mandrel 15 and the open coil is then tight wound onto the mandrel 15 by means of the drive motor 16. When the end of the coil being thus rewound is reached, the coiler 3 is rotated 90° in the direction of the arrow in FIGURE 1 to bring the mandrel 15 into a position such that the tight wound treated coil located thereon is directed towards the exit or delivery side of the coiler assembly, i.e., towards the delivery or outfeed conveyor 29. The coil hoist car 10 is moved into proper position beneath the coil on the mandrel 15 and the platform 11 is raised by the hydraulic cylinder 12 so as to contact the coil, the mandrel 15 then being collapsed so that the platform 11 supports the coil.

This coil is then moved by the coil hoist car 10 off of the now horizontal mandrel 15 to a position above the conveyor means 29 and lowered thereon by the hydraulic cylinder 12. The conveyor means 29 then transports the annealed or otherwise treated tight coil 1b out of the way towards a suitable storage area or other location. It is of particular significance to note that, at the same time that the treated coil 1b is being placed on the conveyor 29 another untreated coil 1 from the conveyor 2 is moved into position on the now horizontal pay off mandrel 9 by the car 4 after which the aforescribed operating cycle may be repeated.

The general arrangement and operation of the ap-

paratus shown in FIGURES 1 and 2 having been explained, attention is now particularly invited to FIGURE 2 which illustrates the internal structure of coiler unit 3. Cylindrical frame member or housing 21 is supported for rotation about an axis extending transversely of its own longitudinal axis upon antifriction bearings 24 and 25 on coaxial shafts 22 and 23. Further, the shaft 23 is rotatably supported in an antifriction bearing 26 carried by a pillow block 27 and the shaft 22 is similarly rotatably supported on an antifriction bearing carried by the pillow block 28.

The shaft 22 is equipped at its outer end with brake means comprising a brake drum 30 which is keyed or otherwise suitably connected to shaft 22 and a brake shoe 15 30a cooperable with brake drum 30 in the usual manner. Shaft 22 is also provided with a bevel gear 31 at its inner end, this gear being connected to the shaft as by keying. A second bevel gear 32 is mounted on the inner end of the opposite coaxial shaft 23 which is operably connected to the drive motor 16 by the coupling 20, gear reducer 19 and coupling 18. The pillow block 27, gear reducer 19 and drive motor 16 are mounted upon a common base or support 33 erected upon a suitable concrete foundation or the like. At the opposite side of the coiler 3, the pillow block 28 and brake means 30, 30a are mounted upon a common base or support 34, also set upon a suitable foundation.

Antifriction bearings 35 and 36 are mounted at the ends (top and bottom as seen in FIGURE 2) of the cylindrical frame member or housing 21. The bearing 35 rotatably supports a circular turntable 37 which in turn supports the bevel gear 38 which is positioned to mesh with the aforementioned gears 31 and 32. The clutch 35, which is clearly shown in FIGURE 4 and will be described in detail later, is adapted to connect or disconnect the gear 38 to or from the turntable 37. In like manner, the bearing 36 supports a similar circular turntable 39 which is connected through a clutch 36 to the bevel gear 40 which likewise meshes with the bevel gears 31 and 32. It will be appreciated that the bevel gears 31, 32, 38 and 40 provide a differential gear arrangement capable of not only imparting opposite rotational movement to the expandable and collapsible mandrels 9 and 15, but, and as will be further explained later, which can be differentially driven, by actuating the brake means 30, 30a, so as to also rotate or revolve the cylindrical housing 21 and the mandrels 9 and 15 as a unit about the common center line of shafts 22 and 23 in a substantially vertical plane. When the clutches 35 and 36 are engaged driving connections are established between the gears 38 and 40 and turntables and when the clutches are disengaged the driving connections are broken and the turntables are free to rotate on the housing 21. As will appear later, the clutches 35 and 36 may be operated independently of each other so that the turntables 37 and 39 and the mandrels 9 and 15 carried thereby may be independently connected to and disconnected from the drive motor 16.

A shaft 41 is rigidly connected to and extends through the turntable 37 and supports and drives the smaller diameter mandrel 9 which is secured thereto and is rotatable therewith. Another similar shaft 42 is rigidly connected to and extends outwardly through turntable 39 for supporting and driving the larger diameter expandable mandrel 15.

The mandrels 9 and 15 are adapted to be selectively expanded and contracted by means of suitable hydraulically actuated mechanisms (not shown) embodied in said mandrels. Hydraulic supply lines 43 and 44 (see FIGURE 4) extend through a suitable bore in the shaft 22, rotary hydraulic joints 47 at the inner end of shaft 22, and shafts 41 and 42 to these mandrel actuating mechanisms. A second pair of hydraulic supply lines 45 and 46 extend through shaft 22 and rotary joints 47 to the

clutches 85 and 86 respectively and conduct to these clutches the fluid pressure which effects engagement and disengagement thereof.

As seen in FIGURE 2, the hydraulic lines 43, 44, 45 and 46 have three way valves 43', 44', 45' and 46' therein and are connected to a pressure supply header 100. Fluid under pressure is supplied to header 100 through pipe 101 by pump 102 and pressure relief lines 43'', 44'', 45'' and 46'' extend from valves 43', 44', 45' and 46' back to the fluid supply sump or container 103. The operation of the valves 45' and 46' to control the clutches 85 and 86 will be explained later.

As best seen in FIGURE 4, the vertically extending shaft 41, which is keyed to the turntable 37 by a key 105, extends downwardly below the turntable and has mounted thereon and keyed thereto an upper clutch housing member 106. A series of driven clutch plates or discs 107 have a vertically slidable keyed or splined connection to the inner hub portion 106' of the clutch housing 106. The lower clutch housing member 108 is secured to the gear 38 as by screws 109 and has an upwardly extending inwardly splined cylindrical ring portion 110 in which the clutch driving discs 111 are supported in interleaved relation with the driven discs 107. The outer peripheries of discs 111 are suitably notched to receive the splines on the inner face of the ring portion 110 of the clutch housing member 108 in well-known manner.

The upper clutch housing member 106, in addition to supporting the driven clutch discs 107, forms an annular fluid pressure chamber or cylinder 112 in which is mounted a vertically movable annular piston 113. A fluid pressure conducting passage 114 extends from the upper portion of chamber 112 into the shaft 41 and downwardly therethrough where it connects with the hydraulic supply line 45 through the rotary hydraulic connection 47.

The clutch 86, which is adapted to effect driving connection between the gear 40 and the turntable 39, is similar in construction to that just described and is similarly connected to the fluid pressure supply line 46. When it is desired to effect driving connection between the gear 38 and the turntable 37 (and thus also with the mandrel 9) the valve 45' is set in the position shown in FIGURE 2 in which a direct connection is provided between the fluid pressure header 100 and the pressure line 45. As the pump 102 maintains fluid under the proper pressure in the header 100 this pressure is applied against the top of the piston 113, moving it downwardly in the annular cylinder 112 and causing it to press the driven clutch discs 107 and the driving clutch discs 111 tightly together to effect driving connection therebetween. When in this condition rotation of the gear 38 will be transmitted through the lower clutch housing 108 and the driving discs 111 to the driven discs 107 and the upper clutch housing 106. As housing 106 is keyed to shaft 41 and as shaft 41 is keyed to the inner hub of the turntable 37, when the clutch 85 is thus engaged a positive driving connection is effected between the gear 38 and the turntable 37 and its mandrel 9.

To release the clutch 85 and thus permit the turntable 37 and mandrel 9 to rotate freely on the bearing 35 without accompanying rotation of the gear 38, as is desired during a coil pay off operation, the valve 45' is turned clockwise through 90° from the position of FIGURE 2 so that the fluid pressure line 45 is connected to the pressure release line 45', thus relieving the fluid pressure in the cylinder 112 with accompanying release of the engagement of the clutch 85.

The operation of the clutch 86 is similarly controlled through the valve 46' which, as seen in FIGURE 2, is in clutch released position. Accordingly, when the apparatus is in the condition of FIGURE 2 and the motor 16 is driven, the turntable 37 and mandrel 9 will be positively rotated while the turntable 39 and mandrel 15 will be disconnected from the driving means and in idle condition.

Of course the valves 45' and 46' may be set as desired so that either one or both of the turntables 37 and 39 may be positively connected to the drive means or released therefrom as desired.

5 Additionally, the cylindrical frame member 21 is provided with three appropriately spaced socket or lock pin receiving members, for convenience in illustration only two of which, 48 and 48', are shown in FIGURE 2. The sockets 48 and 48' are spaced apart 90° about the axis of shaft 23 and the third socket is mounted on a suitable bracket on housing 21 at 90° from the other two. These sockets cooperate with a locking pin 49, which is adapted to be advanced and retracted by a hydraulic cylinder 50 supported upon the pillow block 27. This locking pin 49 10 may be selectively inserted in the three sockets 48 to fix the position of the coiler unit 3 in the desired location about the axes of shafts 22 and 23 for performing the operations of sliding a coil over and onto the smaller diameter mandrel 9 or removing a coil from the larger mandrel 15 when these mandrels are in horizontal position, or paying 15 strip off from the smaller mandrel 9 or winding strip onto the larger mandrel 15 when the mandrels are in vertical position.

Having described the physical structure of the coiler unit 3, its mode of operation will now be more specifically discussed. In order to rotate or revolve the mandrels 9 and 15 about the common axis of shafts 22 and 23 into the desired position, either vertical or horizontal, it is necessary first to apply the brake shoe 30a against the 25 brake drum 30 so as to prevent rotation of the shaft 22 and permit drive of the gear arrangement 31, 32, 38 and 40. Next the locking pin 49 is withdrawn from the pocket 48, 48' or the third similar pocket referred to above, by means of the hydraulic cylinder 50 to permit 30 the coiler unit 3 to rotate about the locked or braked bevel gear 31 when the bevel gear 32 is rotated by the drive motor 16 through shaft 23, gear reducer 19, and couplings 35 18 and 20.

Such rotation of the bevel gear 32, acting through the 40 gears 38 and 40, will rotate the entire coiler unit 3 on the bearings 24 and 25 to bring the expandable and collapsible mandrels 9 and 15 into the desired operating position. As soon as the aforesaid desired position of the mandrels 9 and 15 is reached, the drive motor 16 is stopped and motor 45 and the coiler unit 3 held stationary by application of the brake 17 on the shaft of the motor. The locking pin 49 is moved by hydraulic cylinder 50 into the adjacent socket 48, 48' or the third similar socket referred to above, thus locking the coiler unit 3 in the selected angular position.

50 When the coiler unit 3 is in the vertical position seen in FIGURE 2 and the brakes 30-30a and 17 are released, the drive motor 16, driving through the gear reducer 19 and shaft 23, may be operated to rotate bevel gear 32 which, in turn, will rotate the bevel gears 38 and 40. It 55 will be appreciated that since the brake means 30-30a has been released the bevel gear 31 is free to rotate and consequently, if the clutches 85 and 86 are engaged, the turntables 37 and 39, as well as the mandrels 9 and 15 which are connected to bevel gears 38 and 40, will rotate, 60 but in opposite directions. If either of the clutches 85 or 86 is disengaged by operating the valve 45' or 46' then the corresponding turntable and mandrel will be disconnected from the drive gear 38 or 40 and will remain idle. Such disengagement of the clutches is preferably effected when 65 a mandrel is in its non-operating vertically downward position (see mandrel 15 in FIGURES 2 and 3) and when strip is being paid off of a mandrel in its vertically upright position.

70 It will be understood that the previously described arrangement permits selective vertical positioning and rotation or non-rotation of the expandable mandrels 9 and 15 for either the paying off or tight winding on of a coil of metal strip. Moreover it permits rotating the coiler unit 3 as a whole to place the mandrels 9 and 15 in horizontal position for simultaneously receiving a coil to be

treated and for discharging a treated coil. It is, of course, to be understood that other physical constructions which incorporate the inventive concepts but employ different means might be employed for accomplishing the desired result. One example of such a modified apparatus is illustrated in FIGURE 3.

As there are certain basic similarities between the embodiment of FIGURE 3 and the apparatus previously described like reference numerals are employed for substantially similar or analogous elements. In this modified embodiment the cylindrical housing 21 is provided with a hollow tubular shaft 60 through which extends a shaft 61 supported for rotation at one end in a bearing 62 and operatively connected with the bevel gear 32 of the set of bevel gears 31, 32, 38 and 40. This inner shaft member 61 extends through shaft 60 into a gear train housing 63 and is supported at its other end in a bearing 64 mounted in the wall of housing 63.

The hollow tubular shaft 60 also extends into the housing 63 and is supported by bearings 63' and 65. The inner shaft 61 carries a spur gear 66 freely mounted for rotation thereon. This gear 66 is also operatively connected to a coaxial freely rotatable pinion 67 by a connecting sleeve 68. The pinion 67, in turn, meshes with a spur gear 69 fixedly mounted upon a shaft 70 which is supported in bearing blocks 71, 72 and 73 for rotation within the housing 63. This shaft 70 also has fixedly mounted thereon a wide pinion 74 which meshes with a wide face spur gear 75 fixedly mounted on the hollow tubular shaft 60.

The drive motor 16 is connected through a suitable coupling 90 with a shaft 77 supported for rotation in bearings 76 and 78. This shaft 77 in turn is provided with a pair of spaced and freely rotatable pinions 79 and 80. Intermediate the pinions 79 and 80 there is situated upon the shaft 77 a suitable clutch means 81 which permits selective coupling of either the pinion 79 or the pinion 80 to the shaft 77. Pinion 79 is secured to a sleeve 83 which in turn is connected to a releasable brake 84 which is adapted to permit or prevent rotation of sleeve 83 and pinion 79 on shaft 77.

When the brake 84 is released and the pinion 79 is connected with the shaft 77 by suitable actuation of the clutch 81, then this pinion, since it meshes with the gear 66, will, when motor 16 is operated, impart rotational movement to the entire coiler unit 3 and will swing the expandable mandrels 9 and 15 in a substantially vertical plane into the desired operating position as previously explained. In this instance, the power from the drive motor 16 is effective through the shaft 77, clutch 81, pinion 79, gear 66, pinion 67, gear 69, pinion 74 and gear 75 to rotate shaft 60 and the housing 21 which is secured thereto. On the other hand, if the brake 84 is applied to prevent rotation of pinion 79 and the clutch 81 is actuated so as to couple the pinion 80 to the shaft 77, then pinion 80, which engages with a gear 82 fixedly connected with the shaft 61, will impart rotational movement to the shaft 61 and bevel gear train 31, 32, 38, and 40, thereby imparting rotational movement about their own axes to one or both of the expandable and collapsible mandrels 9 and 15, depending on whether one or both of the clutches 85 and 86 are engaged.

In this arrangement, and for the same reasons as afore-described in conjunction with the embodiment of FIGURES 1 and 2, three sockets or bores 48 are provided on the housing 21. For convenience in illustration only one of these sockets is illustrated and in FIGURE 3 is shown in position to cooperate with locking pin 49 to secure the coiler unit 3 in the angular position in which both mandrels 9 and 15 extend horizontally.

It will be appreciated from the foregoing discussion that in the embodiment of FIGURE 3 it is not necessary to provide a brake device for locking one of the bevel gears of the set 31, 32, 38 and 40 to permit rotation of the entire coiler unit 3 as a whole since, in FIGURE 3, separate gear

trains are provided one of which is capable of imparting rotational movement to the expandable mandrels 9 and 15 about their own axes and the other of which is constructed so that the coiler unit 3, including the mandrels 9 and 15, can be turned or rotated through 360° in a substantially vertical plane, in the same manner and for the same reasons explained in conjunction with the description of FIGURES 1 and 2.

In its other respects the modified embodiment of FIGURE 3 is substantially similar to the embodiment of FIGURES 1 and 2 and the manner of operation is substantially analogous to what has been previously described herein.

In FIGURE 5 there is illustrated a modified form of my apparatus for processing and handling coils of strip metal which is particularly designed for receiving tight wound coils of strip, disposed with their axes horizontal, from a conveyor and rapidly and accurately positioning the coils for, and supporting them during, pay off of the strip to further processing apparatus such as a temper mill. In the apparatus of FIGURE 5 a chain conveyor 120 is adapted to bring tight coils 121 into position to be picked up on the elevator 122 of a coil hoist and transfer car 123 which may be generally similar to the car 4 and its elevator or platform 7 shown in FIGURE 1.

The coil handling unit of FIGURE 5 includes a generally cylindrical housing 124 which carries coil supporting platforms or turntables 125 and 126 at its opposite ends. Expandable mandrels 127 and 128 are carried by 30 and are rotatable with the coil support tables 125 and 126 respectively. Clutches, similar to clutches 85 and 86 of FIGURES 1-4, are provided for independently controlling the driving connection to the mandrels 127 and 128. The housing 124 is supported on a horizontal shaft or trunnion 129 for rotation about its transverse axis. The drive motor 130 is connected through a suitable gear box 131, which may be similar to that illustrated in FIGURE 3, so that the housing 124, coil supports 125 and 126, and mandrels 127 and 128 may be rotated as a unit about the 35 horizontal axis of trunnion 129, and whereby the mandrels 127 and 128 may also be rotated about their own axes when the clutches referred to above are engaged. A four-high type rolling mill 132 is located to receive strip from a coil which is supported on mandrel 128 when the apparatus is in the condition seen in FIGURE 5.

As illustrated, strip from the coil 133, which is supported on the mandrel 128, is being fed through the mill 132 and the mandrel 128 and supporting table 126 are preferably connected to the driving mechanism and 40 rotated at the desired speed. While the coil 133 is being fed to the mill 132 a coil 134 has been removed from the conveyor 120 by the transfer car 123. The car will be moved on its tracks 123' until coil 134 is properly positioned on the now stationary non-rotating mandrel 127 45 which is then expanded. The elevator 122 will then be lowered and car 123 retracted. After the coil 123 has been completely paid off the entire unit will be rotated counterclockwise as seen in FIGURE 5 through 180° so that the positions of the mandrels 127 and 128 will be 50 reversed. The strip of coil 134 will then be properly positioned to be fed through the mill 132 and the mandrel 127 is started to rotate to feed the strip to the mill. While 55 this operation is taking place the coil car 123 will pick up another coil 121 from the conveyor 120 and position it on the now stationary mandrel 128. This cycle is repeated for as long as the installation is maintained in operation.

Substantially the same apparatus as shown in FIGURE 5 may also be used for coiling strip as it is delivered from a rolling mill or other processing operation and for transferring the so formed coils to a conveyor for removal. Such an operation will be understood if it is assumed that the strip in FIGURE 5 is leaving the mill 132 and is moving in a direction opposite to that indicated by the arrow in FIGURE 5 and is being wound onto the driven mandrel 60 65 128. In such a coiling operation, when the complete coil

is formed the housing 124 and the mandrels supported thereby will be rotated in clockwise direction to reverse the positions of the mandrels 127 and 128 and the coil just formed will then be removed from the mandrel 128, rotation of which has been stopped, by the car 23 and transferred to the chain conveyor 120 for removal. Meanwhile the end of the strip from the mill is secured to mandrel 127 for forming another coil.

While there are shown and described herein certain presently preferred embodiments of the invention, it is to be understood that the invention is not limited thereto but may be otherwise variously embodied and practiced within the scope of the following claims.

I claim:

1. Apparatus for processing and handling coils of strip metal including a frame member mounted on a pair of shafts for pivotal movement about a substantially horizontal axis, releasable locking means for holding said frame member against such pivotal movement, a pair of oppositely directed mandrels mounted for rotation on said frame member and having their axes extending at 90° to said horizontal axis of said frame member, and drive means adapted selectively to rotate said mandrels about their axes, while said frame member is held stationary by said locking means or to turn said frame member together with said mandrels as a unit about said horizontal axis of said frame member when said locking member is released.

2. Apparatus for processing and handling coils of strip metal as defined in claim 1 including oppositely facing coil supporting turntables rotatably supported on said frame member coaxially and rotatably with said mandrels, said turntables being horizontally disposed when said axes of said mandrels are vertically disposed.

3. Apparatus for handling coils of strip metal as defined in claim 2 wherein said means for rotating said mandrels rotates them in opposite directions.

4. Apparatus for processing and handling coils of strip metal as defined in claim 1 wherein said mandrels are of different diameters.

5. Apparatus for processing and handling coils of strip metal as defined in claim 1 wherein said mandrels are expandable and collapsible.

6. Apparatus for processing and handling coils of strip metal as defined in claim 1 wherein said means for rotating said mandrels about their axes is adapted to rotate one of said mandrels while the other remains stationary.

7. Apparatus for processing and handling coils of strip metal as defined in claim 1 including a pair of supporting

shafts extending coaxially with said horizontal axis and projecting from opposite sides of said frame member, a base structure for the apparatus, bearing means on said base structure for said supporting shafts, the inner ends of 5 said shafts being spaced apart and having bevel gears mounted thereon, a pair of oppositely extending mandrel shafts rotatably supported on said frame member for carrying said mandrels, said mandrel shafts being coaxially disposed relative to each other and having their inner 10 ends spaced apart, bevel gears mounted on said inner ends of said mandrel shafts and meshing with said bevel gears on said supporting shafts to form a differential gear arrangement, means for driving one of said supporting shafts, and brake means for preventing rotation of the 15 other of said supporting shafts.

3. Apparatus for processing and handling coils of strip metal as defined in claim 1 wherein said means for rotating said mandrels and said means for turning said frame member about said horizontal axis include a differential 20 gear means, a motor connected to one of said supporting shafts for driving said differential gear means, and means for braking the other of said supporting shafts whereby said differential gear means will effect independent and opposite rotation of said mandrels.

25 9. Apparatus for handling coils of strip metal as defined in claim 1 wherein said means for rotating said mandrels about their axes includes independently operable clutch means between said rotating means and said mandrels whereby either one of said mandrels may be rotated while 30 the other mandrel remains stationary.

10. Apparatus for processing and handling coils of strip metal as defined in claim 1 in which one of said supporting shafts is tubular and is secured to said frame member and including a second shaft extending through said 35 tubular supporting shaft, driving gear means between said second shaft and said mandrels, a drive motor, and means for selectively connecting said tubular shaft or said second shaft to said drive motor.
